OIL TEMPERATURE REGULATING DEVICE

Fred M. Young and Ernst Witzel, Racine, Wis.,
assignors to Young Radiator Company, Racine,
Wis., a corporation of Wisconsin

Application November 7, 1936, Serial No. 109,716

5 Claims. (Cl. 184—104)

Our invention relates to means for cooling the lubricating oil of internal combustion engines, particularly those used on airplanes wherein the engine is subjected to various atmospheric temperatures and wherein the lubricating oil is thermally sensitive.

The object of our invention is to first permit the lubricating oil temperature to rise quickly and to a predetermined point after which a further rise in temperature is prevented by a cooperative action of a spring controlled by-pass valve and a heat transfer device operatively connected thereto.

When the present invention is applied to an airplane engine the device is positioned in the open whereby air is forced through the tubes of the core by frontal air pressure, and after the lubricating oil has reached a predetermined temperature and the core has been warmed, the oil is then caused to pass between the tubes of the core by the action of the valve.

One of the objects of the present invention is to make use of the counter flow heat transfer principal by positioning the device parallel to the direction of travel and having the oil inlet in the rear of this device and the oil outlet in front or opposite to the air flow. Another object of the present invention is to provide means whereby round tubes may be closely nested in the housing, and to provide suitable headers and a suitable means for bonding the tubes to the header.

A further object is to increase the air flow through the tubes by flaring the protruding tube ends and stopping the tube ends short of the housing end thus to form a retaining flange around the tube bundles at their ends.

Important objects of our invention are to closely space the tubes and provide a number of baffle partitions through which the tubes extend and are closely embraced thereby the partitions having alternately spaced openings; whereby the oil is forced between the tubes of the bundle transversely, thus to increase the length of travel and cause the oil to closely impinge the surface of the tubes.

To these and other useful ends our invention consists of parts or combinations thereof or their equivalents as hereinafter set forth and claimed and shown in the accompanying drawings in which:

Fig. 1 is a top view of our complete device.

Fig. 2 is a side elevation of the device as shown in Figure 1 having a section cut-away so as to expose fractions of two baffle plates, a section

through the tube plate and a portion of some of the tubes.

Fig. 3 is a rear elevation of the device as shown in Figures 1 and 2.

Fig. 4 is an enlarged end view of three tubes and a fraction of the header.

Fig. 5 is a sectional view taken on line 5—5 of Figure 4.

Fig. 6 is an enlarged transverse section taken on line 6—6 of Figure 2.

Fig. 7 is an enlarged transverse section taken on line 7—7 of Figure 2.

As thus illustrated the shell or housing of the device is designated by numeral 10, this member being preferably made round in cross section, as illustrated in Figure 3. We provide preferably two longitudinal walls 11 and 12 (see dotted lines in Figure 3). These walls are centrally positioned in the shell and spaced apart about as illustrated. We provide preferably two bundles of round tubes 13, these bundles being designated in their entireties by reference characters A and B. Bundle A is positioned in the space formed by partition 11, and bundle B is positioned in the space formed by partition 12. Tubes 13 are preferably round in cross section and closely spaced and occupy practically all of the space formed by members 10, 11 and 12.

We provide preferably two pairs of header plates 14 and 15 through which the ends of the tubes extend, the ends protruding slightly as illustrated in Figure 5. A thin sheet 16, preferably of copper is placed between header plates 14 and 15, the tubes protruding through openings in these copper plates as in the header plates. When the tubes are assembled and the headers placed into position as illustrated fractionally in Figure 3, heat is applied to the tube plates, drum and tube ends, of sufficient temperature to melt the copper sheet 16 which will flow around the tubes and between the headers and provide a liquid and gas tight joint between the headers and tube ends.

The edges of members 11 and 12 are bent at right angles forming flanges. The flanges of member 12 are spaced suitable for the reception of the flanges on member 11. Thus when assembled as illustrated in Figure 3, a chamber 20 is formed. The flanges are bonded together and the entire assembly is bonded to member 10 and to the inside header plates.

Devices of the class are frequently subjected to considerable pressure causing a leak to the atmosphere which is a serious matter in airplane service; therefore, a bonding material such as copper

as described, is desirable. Members 13, 14 and 15 are therefore made of steel or material having a higher fusing point than member 16, thus to make it practical to use the bonding material 16 which 5 requires a considerably higher temperature to fuse than ordinary solder formerly used in devices of the class.

After the tube plates have been secured to the tubes by bonding as described, the tube ends are 10 then flared outwardly as at 21 (see Figure 5), thus to enlarge the opening in the tube ends and reduce the dead space between the same. The tube ends stop short of the end of housing 10 thus providing a forwardly projecting flange forming a pocket 22 15 thereby to assist in directing the air into the tubes as indicated by arrows, it being understood that C designates the front end of the device.

We provide preferably a bracket 19 which is securely bonded to the top of housing 10, as illustrated, and having an inlet opening 25 which registers with an opening in the housing and chamber 20 as at 26 (see Figures 1 and 2). Bracket 19 provides a base for the controlling valve which in its entirety is designated by reference character E 25 including its forwardly extending outlet portion.

Member 19 is made flat on its outer surface and member E registers with this flat surface a gasket 27 being positioned therebetween and the joint made oil tight by means of bolts 28.

30 Member 19 is provided with a chamber 29 having an inlet opening 30 which extends through the housing and into chamber 20, and an outlet opening 31. Bracket 19 is also provided with a chamber 32 having an outlet 33 and inlet openings 34 35 and 35 forming a connection to the front ends of the tube chambers.

Valve E comprises a housing 40 having a valve seat opening 41 which registers with outlet 31. We provide a valve cap 42 which is screw threaded 40 into chamber 40 and is provided with a sleeve 43. A valve 44 is provided with a stem 45 which fits freely into sleeve 43. Spring 46 is adapted to hold the valve on its seat up to a predetermined pressure which will hereinafter be referred to. Member E is provided with a forwardly extending portion 47 having an outlet 48 which extends into the valve chamber formed by housing 40. Outlet 33 intersects outlet 48 as indicated in Figure 7.

We provide a transverse baffle 50 in chamber 20 50 which terminates preferably as at 51 whereby when valve 44 is lifted from its seat, oil may enter inlet 25, pass around baffle 50 at 51 then passing upward and through the valve and out at 48. This is the route taken by the oil when the resistance is too great for it to pass between the tubes of the tube bundle. During this time the heated oil will warm the oil in the tube chambers up to a point where valve 44 will be seated and the oil will then be forced to pass into the front end of the 60 tube chambers through openings 52 which are positioned in the rear ends of partitions 11 and 12 as indicated by dotted lines in Figure 2.

We provide transverse baffle plates 53 and 54 through which the tubes extend and are closely 65 embraced thereby, baffle plates 53 terminating as at 55 and baffle plates 54 as at 56 whereby the oil will pass between the tubes sinuously from inlets 52 to outlets 34 and 35 as indicated by arrows in Figure 2.

70 It will be understood that baffles 53 and 54 may fill the entire space in the housing and have alternately positioned openings which will cause the oil to flow exactly as indicated by arrows.

Thus it will be seen that our device is simple, 75 strong and efficient, that the valve will operate to

permit the oil temperature to rise quickly and further rise will be effectively prevented after the valve has closed and that the device operates on the counter flow principle thus to provide minimum size and cost.

5 Clearly minor detail changes may be made without departing from the spirit of the invention as recited in the appended claims.

Having thus shown and described our invention, we claim:

1. An oil cooling and temperature regulating device of the class described, comprising a housing having a narrow medial passageway and chambers on opposite sides thereof formed by two spaced partition walls and two header plates, 15 bundles of tubes in said side chambers the ends protruding through said header plates and being bonded thereto, a spring held relief valve forming an outlet to said passageway, an inlet connection to said passageway near the rear end thereof, 20 openings to said chambers in said partitions near the rear ends thereof and outlets in the other ends of said chambers, spaced transverse partitions in said chambers through which said tubes extend and having alternately positioned openings, 25 whereby when said valve is closed the oil will pass between the tubes of said bundles sinuously and whereby when the oil cannot pass between the tubes, said valve will lift and the oil pass through said passageway.

30 2. An oil cooling and temperature regulating device of the class described, comprising a housing having a narrow medial passageway and chambers on opposite sides thereof formed by two spaced partition walls and two header plates, 35 bundles of tubes in said chambers the ends protruding through and bonded to said header plates but stopping short of the ends of said housing, the protruding ends being flared outwardly, a spring held relief valve forming an outlet to said 40 passageway, an inlet connection to said passageway near the rear end thereof, openings to said chambers in said partitions near the rear ends thereof, outlets in the other ends of said chambers, spaced transverse partitions in said chambers through which said tubes extend and having alternately positioned openings whereby when said valve is closed, the oil will pass between the tubes of said bundles sinuously and whereby when the oil will not pass between the tubes said valve 50 will lift and the oil pass through said passageway.

3. An oil cooling and temperature regulating device of the class described, comprising a housing having a medial passageway and chambers on opposite sides thereof formed by two spaced partition walls and two header plates, bundles of tubes in said chambers the ends protruding through and bonded to said headers, a spring held relief valve forming an outlet to said passageway, an inlet connection to said passageway near the 60 rear end thereof, openings to said chambers in said partitions near the rear ends thereof, outlets in the front ends of said chambers, a number of spaced transverse partitions in said chambers through which said tubes extend and having alternately positioned openings, whereby when said valve is closed, the oil will be forced to pass between the tubes of said bundles sinuously from the rear to the front thereof and whereby when the oil cannot pass between the tubes of said 70 bundles, said valve will lift and the oil be permitted to pass through said passageway.

4. An oil cooling device of the class described, comprising a housing having a bundle of tubes therein and headers through which said tubes ex- 75

tend forming a core being adapted to be cooled by forcing air through said tubes from front to rear, a low pressure passageway in heat exchange contact with said core having a spring held relief valve outlet, a common inlet at the rear end of said passageway and core, and a common outlet for said valve and the front end of said core, a number of spaced transverse partition walls in said housing through which said tubes extend and having alternate openings, whereby oil will pass from said inlet to said outlet between the tubes of said core sinuously when said valve is closed and in counter heat transfer contact with the air passing through said tubes, and whereby when the oil cannot pass between said tubes, said valve will open and the oil will then pass directly through said passageway and valve.

5. An oil cooling device of the class described, comprising a housing having a bundle of tubes therein and headers through which said tubes

extend, forming a core being adapted to be exposed on an airplane whereby air will be forced through said tubes by frontal pressure, a low pressure passageway in heat exchange contact with said core, having a relief valve outlet, a common inlet at the rear end of said passageway and core, and a common outlet for said valve and the front end of said core, a number of spaced transverse partition walls in said housing through which said tubes extend and having alternately positioned openings whereby oil will pass from said inlet to said outlet between the tubes of said core sinuously when said valve is closed and in counter heat transfer contact with the air passing through said tubes, and whereby when the oil cannot pass between said tubes, said valve will open and the oil then pass directly through said passageway.
